(57) **CLAIM**

The ornamental design for a drawer organizer, as shown and described.

DESCRIPTION

FIG. 1 is a top, front, left side perspective view of a drawer organizer, shown in a closed condition with a divider positioned in a pocket of the drawer organizer, according to our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a top, rear, right side perspective view of FIG. 1; FIG. 9 is a top, front, left side perspective view of the drawer organizer in the closed condition with the divider exploded from the pocket;

FIG. 10 is a top, rear, right side perspective view of FIG. 9; FIG. 11 is a top, front, left side perspective view of the drawer organizer, shown in an opened, expanded condition with the divider positioned in the pocket of the drawer organizer;

FIG. 12 is a front elevation view of FIG. 11;

FIG. 13 is a rear elevation view of FIG. 11;

FIG. 14 is a left side elevation view of FIG. 11;

FIG. 15 is a right side elevation view of FIG. 11;

FIG. 16 is a top plan view of FIG. 11;

FIG. 17 is a bottom plan view of FIG. 11;

FIG. 18 is a top, rear, right side perspective view of FIG. 1; FIG. 19 is a top, front, left side perspective view of the drawer organizer in the opened, expanded condition with the divider exploded from the pocket; and,

FIG. 20 is a top, rear, right side perspective view of FIG. 19.

(Continued)

The broken lines in the drawings depict portions of the drawer organizer that form no part of the claimed design.
